UNITED STATES PATENT OFFICE.

AUSTIN N. OPPENHEIM, OF BALTIMORE, MARYLAND, ASSIGNOR TO OPPENHEIM, OBERNDORF & CO., INC., OF BALTIMORE, MARYLAND, A CORPORATION OF MARYLAND.

DESIGN FOR A DISPLAY SHAPE OF AN ARTICLE OF CLOTHING.

61,051.

Specification for Design.

Patented June 6, 1922.

Application filed March 26, 1921. Serial No. 455,994. Term of patent 14 years.

To all whom it may concern:

Be it known that I, AUSTIN N. OPPENHEIM, a citizen of the United States, and a resident of Baltimore, in the State of Maryland, have invented a new, original, and ornamental Design for a Display Shape of an Article of Clothing, of which the following is a specification, reference being had to the accompanying drawing, forming part thereof.

The figure is a plan view of a shirt showing my design for a display shape adapted thereto.

My design comprises a shape wherein one end thereof is of appreciably greater width than the other and wherein the sides at the edges thereof converge from its wider end to its narrower end.

My design may be adapted or applied to various articles of clothing as a display shape therefor.

I claim:

The ornamental design for a display shape of an article of clothing substantially as shown and described.

AUSTIN N. OPPENHEIM.
